CLAIM

The ornamental design for a gyratory crusher topshell, as shown and described.

DESCRIPTION

FIG. 1 is a perspective view of a gyratory crusher shell;
FIG. 2 is a left side view thereof;
FIG. 3 is a right side view thereof;
FIG. 4 is a side view thereof, the opposite side view being a mirror image thereof;
FIG. 5 is a top view thereof; and,
FIG. 6 is a bottom view thereof.
The broken lines shown in the drawings depict portions of the gyratory crusher topshell that form no part of the claimed design.
